[57] **CLAIM**

The ornamental design for a seat, as shown and described.

DESCRIPTION

FIG. 1 is a front right perspective view of the sectional sleeper section of my new design shown in FIG. 9, the remainder of the seat has not been shown for ease of illustration;

FIG. 2 is a front view thereof;

FIG. 3 is a top view thereof;

FIG. 4 is a right-hand end view thereof;

FIG. 5 is a rear view thereof;
FIG. 6 is a left front perspective of the recliner section of my new design shown in FIG. 9, the remainder of the seat has not been shown for ease of illustration;

FIG. 7 is a top view of the 90° corner wedge section of FIG. 9, remainder of the seat has not been shown for ease of illustration;

FIG. 8 is a rear view thereof; and,

FIG. 9 is a front view of my new design.

The portions of the seat which have not been shown in the drawings form no part of the claimed design.

The broken lines shown in all views represent stitching.
